Joseph R. Corbett, Cincinnati, Ohio, assignor to
Nu Tone, Inc., Cincinnati, Ohio, a corporation
of New York

Application August 7, 1951, Serial No. 16,194

Term of patent 14 years

(Cl. D62—4)

To all whom it may concern:

Be it known that I, Joseph R. Corbett, a citizen of the United States, residing at Cincinnati, in the county of Hamilton, State of Ohio, have invented a new, original, and ornamental Design for a Ceiling Ventilator for Heating and Air Conditioning, of which the following is a specification, reference being had to the accompanying drawing, forming a part thereof.

Figure 1 is a side elevational view of the ceiling ventilator for heating and air conditioning, showing my new design.

Figure 2 is a bottom elevational view thereof.

I claim:

The ornamental design for a ceiling ventilator for heating and air conditioning, substantially as shown.

JOSEPH R. CORBETT.
